A. G. Burns ATTORNEY

UNITED STATES PATENT OFFICE.

KENT L. SEAMAN, OF FORT WAYNE, INDIANA.

GARMENT-SUPPORT.

1,130,343.

Specification of Letters Patent. Patented Mar. 2, 1915.

Application filed August 19, 1912. Serial No. 715,767.

To all whom it may concern:

Be it known that I, KENT L. SEAMAN, a citizen of the United States of America, and resident of Fort Wayne, in the county of 5 Allen and State of Indiana, have invented certain new and useful Improvements in Garment-Supports, of which the following is a specification.

This invention relates to improvements in 10 garment supports especially of that class of supports for trousers, and the object thereof is to afford an expedient by means of which the weight of the trousers will be borne from the hips and ilium bones instead of 15 from the shoulders as with ordinary suspenders. In this manner the upper portion of the body is relieved from the weight of the trousers and the incidental friction of the ordinary suspenders upon the shoulders 20 and back.

Another object is to so construct the appliance that adjustment may be made so as to support the trousers at various heights accordingly as the wearer may desire. And, 25 a further object is to afford a construction that will admit of the trousers being handily disconnected from their supports or replaced without effecting the previous adjustments made.

30 The objects of the invention are accomplished by the construction illustrated by the accompanying drawings in which:

Figure 1 is a perspective view of the apparatus with trousers shown attached thereto, partly cut away; Fig. 2 is a detail view showing the inner face of one of the adjustable supporting members; Fig. 3 is a detail view showing the outer face of one of the stationary anchor plates in which the 40 supporting members are adjustably mounted; and Fig. 4 is a detail view showing a transverse section of a portion of the appliance with the trousers attached thereto.

Similar numerals of reference indicate 45 corresponding parts throughout the several views, and referring now to the same: 1 is a waist belt composed of pliable material and constructed with a laced elastic section 2 in the back portion thereof and with a 50 clasped section 3 in front. The particular form of elastic or lacing or the construction of the clasp used for fastening the waist belt in front, is not material to the invention. The intention is that the waist belt shall 55 fit about the waist snugly immediately above

the hip and ilium bones and receive support therefrom, and at the same time admit of more or less expansion of the body at the waist as occasion may require. Upon the outer side of the waist belt are secured a 60 number of metallic anchor plates 4, each of which has at its upper end a keeper 5, and throughout its central portion a series of button holes 6. The plates are attached to the waist belt in any suitable manner such 65 as by means of eyelets introduced through the openings 7 in the plates. In each of the anchor plates is secured an adjustable supporting member 8 comprising an elongated metallic plate having upon its inner face 70 near the lower end thereof shoulder rivets 9 that are spaced apart to fit in the corresponding pair of button holes in the anchor plate. The upper part of the supporting member is bifurcated and extends up 75 through the keeper 5 and is thereby held from shifting laterally. Upon the inner face of the trousers 10 at the upper edge thereof, are secured a number of metallic stalls 11 so spaced as to correspond with the 80 supporting members 8. These stalls may be secured to the trousers in any suitable manner, and are designed so as to hook over the upper ends of the supporting members respectively. 85

In the use of the appliance the waist belt is first fitted about the waist and each of the supporting members is vertically adjusted in its anchor plate as may be required to hold the trousers to the desired height when 90 the stalls rest in place upon the supporting members. The pliable waist belt held elastically about the waist and the flexibility of the bifurcated supporting members admit of free action of the body and at the same time 95 afford substantial supports for the trousers from which the latter may be quickly disconnected or replaced.

Having described my invention what I claim as new and desire to secure by Letters 100 Patent is:—

1. A device for supporting garments comprising a form-fitting belt, a series of anchor-plates fixed upon the belt, and a corresponding series of supporting members in adjustable connection with the plates, each of said members having two upwardly projecting flexible supports extending parallel to each other and adapted severally to afford support for the garment. 110

2. A device for supporting garments comprised of a form-fitting belt, and a series of supporting members attached to the belt and each being comprised of a flat plate having
5 two upwardly projecting flexible supports that extend parallel to each other and severally afford support for the garment.

In testimony whereof I affix my signature, in presence of two witnesses.

KENT L. SEAMAN.
